United States Patent Office

Des. 209,100
Patented Oct. 31, 1967

209,100

DECANTER

Ernest L. Du Pree, New York, N.Y., and Budd S. Sheesley,
Matawan, N.J., assignors to Schenley Industries, Inc.,
New York, N.Y., a corporation of Delaware

Filed Oct. 10, 1966, Ser. No. 4,221

Term of patent 14 years

(Cl. D58—6)

FIG. 3

FIG. 2

FIG. 1

FIG. 4

We claim:

The ornamental design for a decanter, as shown and described.
